UNITED STATES PATENT OFFICE.

CHARLES P. WILCOX, OF CHICOPEE, MASSACHUSETTS, ASSIGNOR TO THE FISK RUBBER COMPANY, OF CHICOPEE FALLS, MASSACHUSETTS, A CORPORATION OF MASSACHUSETTS.

DESIGN FOR A TIRE.

Application filed March 15, 1926. Serial No. 16,923. Term of patent 14 years.

To all whom it may concern:

Be it known that I, CHARLES P. WILCOX, tire embodying the design; and a citizen of the United States, residing at Chicopee, in the county of Hampden and State of Massachusetts, have invented a new, original, and ornamental Design for a Tire, of which the following is a specification, reference being had to the accompanying drawing, forming part thereof.

Fig. 1 is a fragmentary plan view of a Fig. 2 is a cross-section thereof on line 2—2 of Fig. 1.

I claim:

The ornamental design for a tire as shown.

CHARLES P. WILCOX.
